ELECTRIC LIGHTING FIXTURE

Franklyn S. Schaefer, Great Neck, N.Y., assignor to McPhilben Manufacturing Co., Inc., Brooklyn, N.Y., a corporation of New York

Filed Feb. 2, 1965, Ser. No. 83,663

Term of patent 14 years

(Cl. D48—4)

FIG. 1 is a perspective view of an electric lighting fixture showing my new design.

FIG. 2 is a front elevation thereof.

FIG. 3 is an end elevation thereof, this view being identical with the opposite end.

FIG. 4 is a top plan view thereof.

FIG. 5 is a bottom plan view thereof.

I claim:

The ornamental design for an electric lighting fixture, substantially as shown and described.
